LIQUID FUEL BURNER AND CONTROL

John A. Wilson, Columbus, Ohio, assignor to The
 Lennox Furnace Co., Marshalltown, Iowa, a
 corporation of Iowa

Application July 29, 1948, Serial No. 41,297

27 Claims. (Cl. 158—91)

1

This invention relates to a liquid hydro-carbon fuel burner and the control thereof. It particularly relates to liquid fuel burners of the vaporizing or hydroxylating type. Such burners are commonly referred to as "pot type" burners.

The feeding and regulating of liquid fuel and combustion air in a pot type burner is of paramount importance to obtain efficient and clean burning of fuel. Such burners usually operate at two or more stages of combustion. The present invention is directed to a burner which operates at a low or pilot stage and at a high stage of combustion. The invention is not limited to two stage operation in all of its aspects, however.

Most burners of the vaporizing type include a pot which has a substantially flat bottom with a liquid fuel connection entering near said bottom. The sides of the pot are perforated at intervals from a point near the bottom to a point near the top to supply air for combustion. Just below the top of the pot, there is usually a ring of closely spaced holes which admit air for the final phase of combustion. Various rings and baffles are generally placed in the pot, which is of any well known construction.

In operation, liquid fuel, such as oil, is admitted to the pot and is originally ignited by means of a taper. During the starting phase, the oil burns from the bottom of the pot under the usual pilot ring until the rate of vaporization of the oil exceeds the amount of air being admitted to the section below the pilot ring. The vaporized gases then rise through the pilot ring and mix with air coming in from the holes at the upper section of the pot. Eventually the flame is entirely out of the pot itself and burns at the top thereof.

When the burner is operating on pilot stage, the fire gradually drops back into the pot until it is burning entirely below the pilot ring. In this position, oil at a reduced rate is still admitted to the pot, and in many of the present conventional burners, it flows over the entire bottom area. Such a wide distribution of oil over the pot bottom makes it necessary to burn at a fairly high rate in order to maintain a clean, uniform flame and to maintain sufficient temperature on the pot bottom to vaporize the oil. This is one of the reasons that most conventional pot burners do not maintain a satisfactory pilot flame unless five or six cubic centimeters of oil per minute are fed thereto. (Sixty-three cubic centimeters of oil per minute is equivalent to a rate of one gallon per hour.)

While the burning at a high pilot rate has no particular disadvantage during colder periods of

2

the heating season, it is objectionable in mild weather, as the pilot flame alone is sufficient to overheat the average small home in which such burners are generally installed.

5 Air for combustion to this type of burner is usually supplied by a small continuously operated blower, although some such burners use gravity air flow. In order to maintain air for combustion during the pilot stage and at the same time 10 not overcool the pot, it is customary to reduce the air supplied during the pilot stage period. This is accomplished in at least two ways. One is to open a damper which allows part of the fan air to by-pass to atmosphere. Another is to reduce the motor speed by reducing the voltage supplied thereto.

The reduction of the volume of air supplied during the pilot flame operation is usually from $\frac{1}{3}$ to $\frac{1}{2}$. The disadvantage of this arrangement 20 is that while the air volume is somewhat reduced, it is still supplied to all of the holes in the pot and air is continuously passing through the upper section thereof, which results in chilling the pot. The chilling condition reduces the temperature 25 of the entire pot to the extent that when the oil is again supplied in larger quantities for high fire operation, it does not immediately vaporize. This causes a further chilling of the pot bottom. Eventually the pot comes up to temperature when the oil properly vaporizes, but there is an intermediate period between the pilot and the high flame stages where the fire is smoky and liberates considerable quantities of soot.

Another disadvantage of conventional pot burners is that when a fairly high pilot flame is 30 burning near the pot bottom, the oil inlet pipe reaches a sufficiently high temperature to cause oil to carbonize inside the tube adjacent the point where it enters the pot. To overcome such a condition, a rod is generally placed within the oil tube having a scraper on its inner end and a handle on its outer end. It is necessary for the user to operate this rod at fairly frequent intervals to keep the oil tube open.

45 From the foregoing, it is apparent that most conventional pot burners have three main difficulties which are: (1) too high a pilot flame; (2) a smoky or dirty condition of flame during its transition from the pilot to high fire and back again to pilot; and (3) excessive temperature on the oil inlet tube which causes carbonization of oil and seriously restricts the flow of fuel to the pot.

50 One of the objects of the invention is to provide a burner and control therefor which will

overcome the aforesaid disadvantages of pot type burners.

It is also an object of the invention to supply air to the pilot only during pilot operation, so that the pot is not chilled and the pilot flame heats the pot bottom to a sufficiently high temperature to rapidly vaporize the high fire oil rate when it is supplied to the pot.

It is another object of the invention to cool the oil inlet pipe during the pilot stage by circulating cooling air thereover.

It is an additional object of the invention to provide a pot burner and control in which the transition from the pilot stage to the high fire stage and vice-versa is accomplished rapidly and without objectionable smoke.

Another object of the invention is to provide a very low rate of oil delivery for the pilot flame, so that it will not overheat the house in mild weather.

It is another object of the invention to provide an improved no-air shutter safety control for a forced draft pot type burner.

It is a further object of the invention to provide a novel control for a pot type burner to improve combustion of liquid fuel therein.

It is also an object of the invention to provide an improved air duct and damper control for a forced draft pot type burner.

With these and other objects in view, the invention consists in the construction, arrangement and combination of the various parts of my device whereby the objects contemplated are attained, as hereinafter more fully set forth, pointed out in the claims and illustrated in the accompanying drawings, wherein:

Figure 1 is a vertical sectional view through the burner, only a portion of the pot being shown;

Figure 2 is a sectional view of the burner taken on line 2-2 of Figures 1 and 3;

Figure 3 is a horizontal cross sectional view of the air duct and control system;

Figure 4 is a perspective view of a portion of the air duct and the burner showing the construction of the no-air shutter, with parts of the duct broken away for the sake of clarity;

Figure 5 is an elevational view of the blower and control panel, with the front cover plate removed;

Figure 6 is a transparent perspective view of the air ducts and damper utilized in the burner, the damper being in the high fire position;

Figure 7 is a transparent perspective view of the air duct, looking down on the top thereof, with the shutter in an intermediate position;

Figure 8 is another transparent perspective view of the air ducts and illustrates the shutter in the pilot fire position;

Figure 9 is a partial side view of the furnace and exterior air duct, with parts broken away for the sake of clarity;

Figure 10 is a diagrammatic wiring diagram showing the control for the burner in the high fire position; and

Figure 11 is a diagrammatic wiring diagram of the control shown in the pilot fire position.

Referring specifically to the drawings for a detailed description of the invention, numeral 11 designates an oil burner pot or hydroxylating chamber of any well known construction. The pot 11 is open at its top and is cylindrical in shape, having side walls 12, with a plurality of air holes 13 therein and a bottom 14. A pilot flame housing or chamber is shown at 15 and may be of any well-known construction, the

purpose of the housing being to confine the pilot flame and to supply pilot air to the fuel in a confined location to secure clean and complete combustion without cooling the entire pot. Pilot air is introduced into the pilot chamber through a short air inlet pipe 16 and liquid fuel is supplied to the bottom of the pot 11 at a location within pilot chamber 15 through an oil inlet pipe 17. A front vertical wall of the furnace combustion chamber is shown at 18.

Air for combustion is supplied through a novel duct construction, a portion 19 of which is disposed outside the furnace wall 18, and a portion 21 of which is disposed in the combustion chamber within the wall 18. A partition wall 22 divides the air duct into the two portions 19 and 21, said vertical partition having an opening 23 therein in which a hinged damper or shutter, generally indicated at 24, is disposed.

As shown, for example, in Figures 6, 7 and 8, the air duct portions 19 and 21 are substantially rectangular in shape and a vertical partition 25 divides the duct portion 21 into two chambers 25a and 25b.

The portion 19 of the air duct is provided with a side wall 26 into which an air delivery conduit 27 opens. The air delivery conduit 27 is in communication with an electrically driven fan or blower 28 contained in a casing 29. Preferably the fan 28 operates continuously during the time the burner is being used. Another side wall 32 of duct portion 19 is provided with an opening 31 therein which is normally closed by a no-air shutter generally indicated at 33, for a purpose hereinafter described.

The oil pipe 17 extends through the lower portion of chamber 25a and through an air aperture 34 in partition 22 which is somewhat larger in diameter than oil pipe 17 and which is disposed below duct portion 19. An air opening 30 is provided in the lower portion of chamber 25b and communicates directly with the combustion chamber.

As best shown in Figures 1, 2 and 3, the shutter 24 is provided with two vanes or wings disposed at an angle to each other and is pivotally supported on flanges 35 of a plate 40 which is secured to the front furnace wall 18. A bar of metal 37 is secured to the shutter 24 between the vanes, and pivot pins 36 engage the bar to pivotally support the shutter, nuts or other suitable means being provided for retaining the pivot pins 36 in place.

Also secured to one of the vanes of shutter 24 is a bracket provided with an upper ear 38 and a lower ear 42. A rod 39 having a hook on its inner end is releasably secured in an opening in ear 38, the purpose of which is hereinafter described. A coil tension spring 41 is releasably secured at one end in an opening in ear 42 and is releasably secured at its other end to a substantially air tight vertical partition 45 welded to duct portion 19. Rod 39 extends through a small opening in partition 45. The spring 41 tends to maintain the shutter 24 in the position shown in Figure 4, since it is attached thereto on one side of the pivot points, which is the high fire position.

An insulating panel 46 is provided for mounting electrical equipment and is supported from partition 45 by studs 89 to which screws are secured. The panel 46 is provided with an opening 47 therein, through which rod 39 extends. The rod 39 terminates a short distance in front of panel

A thermally operated warp bar assembly 49 is mounted on panel 46 and operates a pivoted extension or lever 48 which is in engagement at all times with the end of rod 39, due to the bias of spring 41. Obviously, movement of warp bar extension 48 to the left, as viewed in Figure 4, rotates shutter 24 about pivots 36, and disposes it in the dotted line position shown in Figure 4, which is the pilot fire air position, as will be explained. In other words, the shutter 24 closes an opening 23b on one side of partition 25 and opens an opening 23a on the other side of partition 25, or vice versa, depending on the demand for high or pilot fire operation. The partition 25 provides a stop for shutter 24 in either position. A stud 51, with suitable nuts thereon, is mounted on the panel 46 and provides a stop for extension 48 in its outward movement.

As best shown in Figure 4, the no-air shutter 33 is pivotally supported on a plate 52 secured to side wall 32 of duct portion 19. The plate 52 has inturned ears 53 formed thereon, which provide journals for a shaft 56 for no-air shutter 33. The shutter 33 is formed with flanges 54 and a rod 57 is secured to said flanges. The rod 57 extends through a kidney shaped hole 58 in panel 46 and through a similarly shaped hole 59 in partition 45.

A no-air switch, generally indicated at 61, is mounted on the front of the insulating panel 46 and includes a relatively fixed flexible contact arm 62 and a flexible contact arm 63, which is adapted to be moved by an enlarged end 51a of rod 57, which extends a short distance in front of panel 46 into engagement with the under side of contact arm 63. The end 51a of rod 57 travels in an arc and reaches its highest point approximately when the shutter 55 is closed. Contacts 64 and 65 are provided on contact arms 62 and 63, respectively.

Referring now to Figures 10 and 11, the oil burner control includes a transformer having a primary coil 66 and a secondary coil 67 to reduce a 110 volt line to 24 volts, for example. A limit switch 68, of any well known construction, is shown in the 110 volt circuit, so that if excessive temperatures are produced by the burner, the entire system, except the blower, will be rendered inactive. The control also includes a room thermostat diagrammatically illustrated at 69 and an oil valve at 71. The oil valve is preferably electrically operated and is controlled by a warp relay switch generally indicated at 73, which also controls the operation of warp switch 49. The warp relay 73 includes a thermostatic warp bar 75 and an electrical heater 74. The warp bar is provided with an extension 80 on which contacts 76 and 77 are carried, which contacts are adapted to engage respectively with fixed contacts 78 and 79 mounted on panel 46, in positions which are not shown.

The oil valve 71 is of any standard type utilized with pot type burners. The valve never entirely prevents the flow of fuel to the vaporizing pot 11. When the thermostat 69 is not calling for heat, the valve 71 permits sufficient fuel to flow through pipe 17 to maintain the desired low pilot flame. When the room thermostat calls for heat, the oil valve 71 opens completely and permits sufficient flow of fuel through pipe 17 to maintain the desired high flame.

The warp element 49 includes an electrical heater 82 and a thermostatic warp bar 83. The aforementioned arm 48, which engages with rod

39 to operate shutter 24, is pivoted to a bracket 86 mounted on panel 46.

Suitable terminals 84a for the oil valve, transformer and room thermostat are disposed on the panel 46. A cover plate 85 is provided to enclose the panel 46. Screws 90 may be removed for gaining access to the electrical panel 46.

Angles 91 are secured to the front plate 40, which front plate is secured to the front furnace wall 18 by studs and nuts 92. Screws 93 secure the air duct portion 19 to the angles 91. Furnace studs 94 secure the front wall 18 of the furnace to the remainder thereof. The internal air duct portion 21 is preferably welded to the wall 18, and the inclined wall 20 thereof, through which the pilot air pipe 16 extends, is preferably screwed to the remainder of duct portion 21.

It is obvious, therefore, that the entire air duct and control assembly are made up of several independent readily detachable units so that, if it is necessary to repair or replace parts, there is no problem of assembly and disassembly. Such construction is also of advantage in manufacturing on a mass production basis, as the complete units may be brought into a main assembly line and may also be stocked. For example, the electrical panel 46 is readily accessible by removing the screws 90 and taking off the front cover plate 85. The electrical panel itself may be removed by unscrewing screws in the studs 89 and removing wires from the terminals 84a. It will be noted that the rods 39 and 57 do not interfere with removal of panel 46, because they extend freely through the holes therein.

If it is desired to remove the entire air duct portion 19, including shutter 24, nuts 92 are removed and the entire unit may be taken off the furnace. After the rod 39 is released from ear 38, and spring 41 from ear 42, the air duct portion 19 may be disassembled by removing screws 93. It is possible to reach ears 38 and 42 through opening 23 in plate 40. This plate 40 is shown as partition 22 in Figures 6, 7 and 8, which are merely diagrammatic.

If the entire assembly is to be removed, furnace studs 94 are unscrewed, and the entire unit may be moved forwardly, since the air pipe 16 and oil pipe 17 extend freely through wall 20.

Clearly the reverse of the above is followed in assembling any of the component parts of the air duct and control. Also, the fan 28 and its casing 29 and duct 21 may be readily removed as a unit by removing screw 97.

Operation

The completely assembled burner operates in the following manner. Assuming that the line L1, L2 is connected to a source of power, it is obvious that the fan, which is preferably driven by an alternating current 110 volt motor, operates continuously, regardless of the condition of the remainder of the circuit or apparatus. Leads 100 and 101 connect the fan motor to line L1, L2. Thus, combustion air is continuously supplied during the entire heating season. Furthermore, the primary and secondary coils 66 and 67 of the transformer are energized continuously, unless the limit control, shown diagrammatically at 68, breaks the circuit because of excessive heat due to combustion.

Placing the limit switch 68 in the circuit to the primary 66 of the transformer provides a safety factor if, for some accidental reason, the pilot flame is extinguished. If this occurs, the entire pot bottom may flood with oil, and if the user again starts the burner without first drain-

ing the pot, excessive temperatures may develop. As will be seen as the description progresses, if the limit switch operates, the damper 24 is positioned on high fire very quickly, if it is not already there, and the oil supply is not increased to the high fire rate as electric valve actuator 72 is deenergized. If the limit switch 68 then cycles, because room thermostat 69 is calling for heat, the oil valve 71 will also cycle between pilot fire and high fire operation, but the air flow remains high. The pot does not, however, have sufficient time to cool down to a point where the oil does not vaporize rapidly when high fire operation is initiated. It may be noted that under normal conditions, the limit switch will very seldom function, if at all. It is purely a safety device for protection from abnormal conditions.

Since the fan 28 operates continuously, the velocity of the combustion air maintains the no-air shutter 33 in the closed position at all times, as shown diagrammatically in Figures 10 and 11. The outlet from fan 28 is disposed directly opposite the no-air shutter in air duct portion 19 for this purpose. Contacts 64 and 65 are, therefore, maintained closed because rod 51 secured to no-air shutter 33 raises switch arm 63 to close said contacts. Obviously, if contacts 64, 65 are opened because no air or insufficient air is being supplied by fan 28 for any reason, such as a burned out motor or low voltage, no energy is supplied to the 24 volt circuit. The oil valve 71 will then go to or remain on pilot fire operation and shutter 24 will go to or remain in high fire position, as will be clear as the description proceeds. If the fan is completely inactive, gravity air flow through the no-air shutter opening 31 and through opening 30 will be supplied to the combustion chamber. Air will be supplied in small amounts through opening 34 and air inlet pipe 16. This gravity flow of air is sufficient to maintain the pilot flame and to consume any oil in the pot at the time of blower failure. This again is purely a safety factor and takes care of an exceptional abnormal condition. When no air shutter is open, the control circuit is dead and the thermostat cannot open the oil valve. Again, such a condition would ordinarily seldom, if ever, occur during the life of the apparatus, since small motors of this type very infrequently fail if given normal care, and very low voltage conditions or interruptions of power supply are exceptional.

Assuming now that the limit switch 68 is closed, that the fan 28 is operating properly, and that the room thermostat 69 is not calling for heat, the apparatus will be in the condition shown in Figure 11, with room thermostat contacts 102 and 103 open and no-air contacts 64, 65 closed. The heater 74 of the relay switch 73 is deenergized, and warp bar 75 is cold. Contacts 76, 78 of relay switch 73 are, therefore, closed, and contacts 77 and 79 are open. Electric valve actuator 72 of oil valve 71 is deenergized, and oil valve 71 is supplying a reduced pilot flame fuel supply. Heater 82 of switch 49 is, therefore, energized and warp bar 83 is hot, thus moving the warp bar extension 84 to the right as viewed in Figure 3, and swinging arm 48 to the left about the pivot of bracket 86. The rod 39 is, therefore, pushed inwardly and damper or shutter 24 is rotated to the pilot position shown in dotted lines in Figure 3 and shown in full lines in Figure 11. Combustion air from fan 28 then enters air duct portion 19, passes through opening 23a in partition 22, into chamber 25a, and thence through pilot air pipe 16 into pilot flame chamber 15. Excess air supplied to

chamber 25a is directed to atmosphere through opening 34. It will be noted that oil pipe 17 is cooled by surplus air passing thereover when the burner is operating at the pilot stage. Due to the reduced flow of oil at this time, carbonization may occur, but by cooling the oil pipe 17, such carbonization is effectively retarded. On high fire, cooling of the oil pipe 17 is not essential, as the flame is burning from the top of the pot 11 and the temperature adjacent the pilot chamber 15 and inlet of oil tube or pipe 17 is lower than on pilot flame.

Assuming now that the room thermostat calls for heat, thermostat contacts 102, 103 close and the burner goes on high fire operation, as shown in Figures 3 and 10, in the following manner. Closing of room thermostat contacts 102, 103 energizes heater 74 of relay switch 73. Shortly after, warp bar 75 begins to move to the right, as viewed in Figure 11 and contacts 76, 78 open. This immediately deenergizes heater 82 of warp switch 49, and as warp bar 83 cools fairly rapidly, it moves to the left as viewed in Figure 3, and arm 48 moves to the right, because spring 41 pushes rod 39 against arm 48. Shutter 24, therefore, moves to the high fire position shown in full lines in Figures 3 and 10 within a relatively short period of time and before warp bar 75 of relay switch 73 has closed contacts 77, 79. Full combustion air flow is thus supplied to the pot 11 before the high fuel rate for high fire is delivered thereto. The combustion air from fan 28 now enters chamber 19, passes through opening 23b into chamber 25b, and thence into the pot 11 through opening 30 in the air duct and holes 13 in the pot. By supplying combustion air at a high rate prior to supplying fuel at a high rate, sufficient air to support combustion of the increased fuel supply is insured and no smoke or soot is produced during the transition period.

The warp bar 75 of relay switch 73 continues to move, and shortly after damper or shutter 24 is in the high fire position, contacts 77, 79 are closed, thus energizing electric valve actuator 72 and opening oil valve 71 to supply a high oil rate to pot 11 through oil pipe 17.

When room thermostat 69 is satisfied, contacts 102, 103 open and immediately deenergize heater 74 of relay switch 73. Wrap bar 75 cools fairly quickly and, shortly after contacts 102, 103 were opened, contacts 77, 79 open, thus deenergizing electric oil valve actuator 72 and partially shutting oil valve 71, so that pilot flow of fuel is supplied to pot 11 through oil pipe 17. However, shutter 24 remains in the high fire position for about 1½ to 2 minutes to completely burn residual fuel and to provide scavenging of the combustion space. The formation of soot or smoke during the transition period from high to pilot stage is, therefore, prevented. The delay in moving shutter 24 to pilot position is effected because a time interval occurs while warp bar 75 cools sufficiently to close contacts 76, 78 to energize heater 82 of switch 49. Thereafter, another time interval occurs while warp bar 83 of switch 49 flexes a sufficient distance to rotate shutter 24 completely to the pilot position. The shutter 24 obviously passes through a plurality of intermediate positions between high and pilot fire, and vice versa, one of which is shown in Figure 7.

From the foregoing, it will be clear that, if for any reason the limit switch 68 operates or the no-air contacts 64, 65 open, the oil valve goes on pilot operation, because electric oil valve 72 is deenergized. Also, relay switch heater 74 is deenergized

and heater 82 of switch 49 cannot be energized under such circumstances, even though room thermostat 68 calls for heat. Shutter or damper 24, therefore, assumes or remains in the high fire position, depending on the condition of the circuit when no-air contacts 64, 65 open, or the limit switch 63 operates to break the transformer circuit.

The burner and control described above overcomes the inherent defects of most conventional 10 pot burners, for the following reasons:

By preventing a high rate of delivery of combustion air to the pot during the pilot stage, and supplying air to the pilot only, the pot is not chilled and the pilot flame heats the pot bottom to a sufficiently high temperature (above 500° F.) to rapidly vaporize the high fire oil rate when it is delivered to the pot.

By circulating cooling air over the oil inlet pipe during the pilot stage, its temperature is maintained sufficiently low at all times to retard carbonization.

The burner herein described cycles between high and pilot stages without danger or the production of smoke or soot.

A dependable oil pilot rate as low as 1½ cubic centimeters per minute may be maintained. One cubic centimeter of oil contains approximately 37 B. t. u., so that the heat input would be 55 B. t. u. per minute or 3300 B. t. u. per hour. One gallon of oil would supply the pilot flame for about 42 hours. Such a rate does not cause discomfort during mild weather.

The burner and control is extremely safe in operation, is easy to construct, assemble, install, and repair, and is inexpensive to manufacture.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

I claim as my invention:

1. Control apparatus for the pot type liquid fuel burners including a pot and a housing forming a pilot flame chamber disposed therein, said control apparatus including a control panel, a fuel supply means having its outlet adapted to communicate with the pot adjacent the pilot flame chamber, means adapted to increase the flow of fuel to said pot upon a demand for heat and to decrease it when said demand is satisfied, means adapted to supply combustion air to burn said fuel, means adapted to increase the flow of combustion air to said pot upon a demand for heat and adapted to direct a decreased flow of air to said pilot chamber and substantially exclude air to said pot otherwise when the demand for heat is satisfied, said last means including a thermostatically responsive warp bar mounted on said panel, means for controlling the heating of the warp bar in response to heat demand, an air damper, means whereby said air damper controls the air flow, and means extending through said panel and movable by said warp bar for controlling the position of said damper to supply said increased or decreased air flow.

2. Control apparatus as set forth in claim 1 wherein the means for supplying combustion air comprises a continuously operating single speed blower.

3. Control apparatus as set forth in claim 1 wherein the means for supplying combustion air

comprises a continuously operating single speed blower and wherein means responsive to abnormal operation of said blower is provided to immediately decrease said fuel supply.

5. Control apparatus as set forth in claim 1 wherein the means for supplying combustion air comprises a continuously operating single speed blower and wherein means responsive to abnormal operation of said blower is provided to immediately decrease said fuel supply and to move said air damper to the position wherein it would normally increase the flow of combustion air to said pot.

5. Control apparatus for pot type liquid fuel burners including a pot, a housing forming a pilot flame chamber disposed therein and a fuel supply means adapted to have its outlet adjacent said pilot flame chamber, said control apparatus including means adapted to increase the flow of fuel to said pot upon a demand for heat and to decrease it when said demand is satisfied, means adapted to supply combustion air to burn said fuel comprising a continuously operating blower adapted to deliver combustion air at a constant

25 volume and pressure, means adapted to increase the flow of combustion air to said pot upon a demand for heat and adapted to direct a decreased flow of air to said pilot chamber and substantially exclude air to said pot otherwise

30 when said demand for heat is satisfied, said last means including firstly a divided air duct having one portion thereof adapted to communicate with said pilot chamber and with the atmosphere and the other portion thereof adapted to communicate

35 with the pot proper, secondly a damper adapted to direct combustion air into one or the other duct portions, and thirdly means for operating the damper in response to the requirements for heat, and means adapted to immediately decrease the supply of fuel to the burner and to move said damper to the position wherein it normally effects maximum air flow to said burner upon a predetermined abnormal decrease in the supply of combustion air to said blower.

45. Control apparatus for pot type liquid fuel burners including a pot and a housing forming a pilot flame chamber disposed therein, said control apparatus including a control panel, a fuel supply means having its outlet adapted to

50 communicate with the pot adjacent said pilot flame chamber, means adapted to increase the flow of fuel to said pot upon a demand for heat and to decrease it when said demand is satisfied, a continuously operating blower adapted to supply combustion air, means adapted to increase the flow of combustion air to said pot upon a demand for heat and adapted to direct a decreased flow of air to said pilot chamber and substantially exclude air to said pot otherwise

55 when the demand for heat is satisfied, said last means including a movable damper, a thermostatically responsive warp bar mounted on said panel, means extending through said panel operated by said warp bar to move said damper,

60 an electrical heater for said warp bar and a circuit including said heater for controlling the operation of said warp bar in response to requirements for heat.

7. Control apparatus for pot type liquid fuel burners including a pot and a housing forming a pilot flame chamber disposed therein, said control apparatus including a control panel, a fuel supply means having its outlet adapted to communicate with the pot adjacent said pilot flame chamber, means adapted to increase the flow of

fuel to said pot upon a demand for heat and to decrease it when said demand is satisfied, a continuously operating blower adapted to supply combustion air, means adapted to increase the flow of combustion air to said pot upon a demand for heat and adapted to direct a decreased flow of air to said pilot chamber and substantially exclude air to said pot otherwise when the demand for heat is satisfied, said last means including firstly a movable damper, secondly a thermostatically responsive warp bar mounted on said panel, thirdly means extending through said panel and moved by said warp bar to in turn move said damper, and fourthly a divided air duct including two passages, one of which is adapted to communicate at its outlet with said pilot chamber and the atmosphere and the other of which is adapted to communicate at its outlet with the area adjacent said pot proper, means for controlling the heating of the warp bar in response to heat demand, said passages also having inlets to receive air from said blower, and said damper being movable to substantially prevent the flow of air through one or the other of said inlets.

8. Control apparatus for pot type liquid fuel burners including a pot, a housing forming a pilot flame chamber disposed therein and a fuel supply means having its outlet adjacent said pilot flame chamber, said control apparatus including means adapted to increase the flow of fuel to said pot upon a demand for heat and to decrease the flow of fuel when said demand is satisfied, means adapted to supply combustion air to burn said fuel, thermostatically controlled means adapted to increase the flow of combustion air to said pot upon a demand for heat, and adapted to direct a decreased flow of air to said pilot chamber and to substantially exclude air to said pot when said demand for heat is satisfied, said last means including a divided air duct having one portion thereof adapted to communicate with said pilot chamber and the other portion thereof adapted to communicate with said pot proper, a damper for directing combustion air into one or the other duct portions, and means for operating said damper in response to requirements for heat.

9. Control apparatus for pot type liquid fuel burners including a pot, a housing forming a pilot flame chamber disposed therein and a fuel supply means having its outlet adjacent said pilot flame chamber, said control apparatus including means adapted to increase the flow of fuel to said pot upon a demand for heat and to decrease the flow of fuel when said demand is satisfied, means adapted to supply combustion air to burn said fuel, thermostatically controlled means adapted to increase the flow of combustion air to said pot upon a demand for heat, and adapted to direct a decreased flow of air to said pilot chamber and to substantially exclude air to said pot when said demand for heat is satisfied, said last means including a divided air duct having one portion thereof adapted to communicate with said pilot chamber and the other portion thereof adapted to communicate with said pot proper, a damper for directing combustion air into one or the other duct portions and means for operating said damper in response to the requirements for heat, a portion of said fuel supply means adjacent its outlet being disposed in the portion of said duct communicating with said pilot chamber.

10. Control apparatus for pot type liquid fuel burners including a pot, a housing forming a

pilot flame chamber disposed therein and a fuel supply means having its outlet adjacent said pilot flame chamber, said control apparatus including means adapted to increase the flow of fuel to said pot upon a demand for heat and to decrease the flow of fuel when said demand is satisfied, means adapted to supply combustion air to burn said fuel comprising a continuously operating blower adapted to deliver combustion air at a constant volume and pressure, means adapted to increase the flow of combustion air to said pot upon a demand for heat, and adapted to direct a decreased flow of air to said pilot chamber and to substantially exclude air to said pot when said demand for heat is satisfied, said last means including a divided air duct having one portion thereof adapted to communicate with said pilot chamber and the other portion thereof adapted to communicate with said pot proper, a damper for directing combustion air into one or the other duct portions, and means for operating said damper in response to requirements for heat.

11. Control apparatus for pot type liquid fuel burners including a pot, a housing forming a pilot flame chamber disposed therein and a fuel supply means having its outlet adjacent said pilot flame chamber, said control apparatus including means adapted to increase the flow of fuel to said pot upon a demand for heat and to decrease the flow of fuel when said demand is satisfied, means adapted to supply combustion air to burn said fuel comprising a continuously operating blower adapted to deliver combustion air at a constant volume and pressure, means adapted to increase the flow of combustion air to said pot upon a demand for heat, and adapted to direct a decreased flow of air to said pilot chamber and to substantially exclude air to said pot when said demand for heat is satisfied, said last means including a divided air duct having one portion thereof adapted to communicate with said pilot chamber and the other portion thereof adapted to communicate with the pot proper, a damper for directing combustion air into one or the other duct portions, and means for operating the damper in response to the requirements for heat.

12. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases.

13. Control apparatus for pot type burners including a pot and a housing forming a pilot

chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber having an opening therein, and a shutter for closing said opening when said blower delivers a sufficient amount of air.

14. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said third chamber being adapted to accommodate said oil conduit.

15. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third

chambers when additional heat is required and to close the inlet between the first and third chambers when the requirement for heat decreases, said third chamber being adapted to accommodate said oil conduit and extending through the outlet therein to the atmosphere.

16. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said third chamber being adapted to accommodate said oil conduit and extending through the outlet therein to atmosphere, said second and third chambers being disposed side by side with a partition therebetween.

17. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said third chamber being adapted to accommodate said oil conduit and extending through the outlet therein to atmosphere, said second and third chambers being disposed side by side with a partition therebetween, and said first chamber being disposed in a substantially horizontal alignment with said second and third chamber.

18. Control apparatus for pot type burners including a pot and a housing forming a pilot chamber disposed therein, said pot being disposed in a combustion chamber, and a conduit for supplying oil to said pot, a continuously operating blower adapted to supply air, on air duct assembly, a moveable damper in the air duct assembly,

said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, and a removable control panel disposed in front of said first chamber, said means responsive to heat requirements being at least partially supported on said control panel.

19. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a moveable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said air duct assembly adapted to be detachably secured to a wall forming said combustion chamber.

20. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a moveable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said air duct assembly and damper adapted to be

5 16
detachably secured as a unit to a wall forming said combustion chamber.

21. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a moveable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said air duct assembly, said damper and at least a portion of said means responsive to said requirements adapted to be detachably secured as a unit to a wall forming said combustion chamber.

22. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a moveable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber and said damper adapted to be detachably secured as a unit to a wall forming said combustion chamber.

23. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a moveable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with

with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber adapted to be disposed outside said combustion chamber and said second and third chambers adapted to be disposed within the combustion chamber.

24. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber adapted to be disposed outside said combustion chamber and said second and third chambers adapted to be disposed within the combustion chamber, said first chamber and damper adapted to be detachably secured as a unit to said second and third chambers.

25. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly, said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber adapted to be disposed outside said combustion chamber and said second and third chambers adapted to be disposed within the combustion chamber.

5 disposed within the combustion chamber, said first chamber and damper adapted to be detachably secured as a unit to said second and third chambers and an electrical panel supporting at least part of said means responsive to heat requirements and adapted to be supported by and removable with said first chamber.

26. Control apparatus for pot type burners including a pot and a housing forming a pilot chamber disposed therein, said pot being disposed in a combustion chamber, and a conduit for supplying oil to said pot, a continuously operating blower adapted to supply air, an air duct assembly, a movable damper in the air duct assembly,

15 said air duct assembly including a first chamber into which said fan discharges, a second chamber having an outlet adapted to communicate with said combustion chamber and an inlet adapted to communicate with said first chamber, a third chamber having one outlet adapted to communicate with said pilot chamber, another outlet adapted to communicate with the atmosphere and an inlet also adapted to communicate with said first chamber, said damper being movable to close one of said inlets and open the other and vice versa and means responsive to heat requirements for moving said damper to open the inlet between the first and second chambers and to close the inlet between the first and third chambers when additional heat is required and to close the inlet between the first and third chambers when the requirement for heat decreases, said first chamber adapted to be disposed outside said combustion chamber and said second and third chambers adapted to be disposed within the combustion chamber, said first chamber and damper adapted to be detachably secured as a unit to said second and third chambers and an electrical panel supporting at least part of said means responsive to heat requirements and adapted to be supported by and removable with said first chamber.

20 25 30 35 40 45 50 55 60 65

27. Control apparatus for pot type liquid fuel burners including a pot, a housing forming a pilot flame chamber disposed therein, and a fuel supply means having its outlet adjacent said pilot flame chamber, said control apparatus including means adapted to increase the flow of fuel to said pot upon a demand for heat and to decrease it when said demand is satisfied, means adapted to supply combustion air to burn said fuel, a divided air duct having one portion thereof adapted to communicate with said pilot chamber and the other portion thereof adapted to communicate with said pot proper, a damper in said air duct arranged to increase and decrease the flow of air to the pot proper and to respectively decrease and increase the flow of air to the pilot chamber, and means for operating said damper in response to the requirements for heat.
